BREAKWATER

Ted A. Johnson, Holdrege, Nebr., assignor to The Central Nebraska Public Power and Irrigation District, Holdrege, Nebr.

Filed Aug. 2, 1965, Ser. No. 86,406

Term of patent 14 years

(Cl. D18—2)

FIG. 1

FIG. 2

FIGURE 1 is a perspective view of my new design for a breakwater.

FIGURE 2 is a front elevational view of my new design for a breakwater, the rear elevational view and the two side elevational views being identical thereto.

I claim:

The ornamental design for a breakwater, as shown and described.
